(Cl. D26—14)

To all whom it may concern:

Be it known that we, James M. Robinson, Leonard J. Greshel and Donald A. Lewis, citizens of the United States of America, residing at Galion, in the county of Crawford and State of Ohio, have invented a new, original, and ornamental Design for a Desk Stand for a Hand Telephone, of which the following is a specification, reference being had to the accompanying drawing, forming a part thereof.

Figure 1 is a perspective view of a desk stand for a hand telephone, showing our new design;

Figure 2 is a side elevational view thereof;

Figure 3 is a top plan view thereof; and

Figure 4 is a rear elevational view thereof.

The dominant features of our design reside in those portions shown in full lines.

We claim:

The ornamental design for a desk stand for a hand telephone, as shown and described.

JAMES M. ROBINSON.
LEONARD J. GRESHEL.
DONALD A. LEWIS.
